UNITED STATES PATENT OFFICE.

WILLIAM L. FRISBIE, OF SYRACUSE, NEW YORK, ASSIGNOR OF ONE-HALF
TO JAMES C. KENYON, OF SPRINGFIELD, MASSACHUSETTS.

LAWN-MOWER.

SPECIFICATION forming part of Letters Patent No. 379,949, dated March 27, 1888.

Application filed July 14, 1887. Serial No. 244,274. (No model.)

To all whom it may concern:

Be it known that I, WILLIAM L. FRISBIE, a citizen of the United States, residing at Syracuse, county of Onondaga, and State of New 5 York, have invented a new and useful Lawn-Mower, of which the following is a specification.

The first part of my improvements relates to mechanism for adjusting the position of the stationary cutter relative to the rotary cutter; the second part to an adjustable journal-bearing for the cutter-shaft; the third to a handle-holding device; the fourth to a traction-roller, and the fifth to a truck-wheel journal and 15 journal-bearing; and the invention consists in the combination and construction as herein-after described, and more particularly pointed out in the claims.

My invention is fully illustrated in the accompanying drawings, in which—

Figure I is an elevation of the outside of part of the wall or side of the machine seating one end of the stationary cutter. Fig. II shows the same seen in reverse. Fig. III is an outside view of the stationary cutter-moving device. Fig. IV shows the same in reverse. Fig. V is an edge view of the same part. Fig. VI is an end view of the stationary cutter. Fig. VII is a front elevation of the above-mentioned parts assembled and in partial section on the dotted line $\alpha\alpha$ of Fig. I. Fig. VIII is an elevation of one end of the rotary cutter with a portion of the side wall of the machine shown in section. Fig. IX is an end view of the adjustable journal-bearing sleeve for the cutter-shaft. Fig. X is an elevation or side view of the handle-holder belonging to one side of the machine, and showing one fork of the handle, while Fig. XI is the same view of the holder 30 with stud-bolt G in section, showing the fork of the handle in another position. Fig. XII is an edge view of part of one fork of the handle. Fig. XIII is a plan view of part of a traction-roller. Fig. XIV is a side elevation 40 of one wheel thereof. Fig. XV is a view of details composing the journal and journal-bearing of one truck-wheel. Fig. XVI is a vertical section through the journal and journal-bearing of a truck-wheel. Fig. XVII is 45 a side elevation of the lawn-mower with the cap or guard plate removed. Fig. XVIII is

a detached view of the cap or guard plate. Fig. XIX is a longitudinal vertical section with parts in elevation. Fig. XX is a detail section of a portion of one of the side walls. 55 Fig. XXI is a side elevation of the journal-bearing sleeve.

A is a side wall of a lawn-mower, including the cap or guard plate, and, as shown in Fig. I, is provided with an opening, a , therethrough in the form of a vertical slot, within which the bolt b of the stationary cutter is inserted and has a limited movement therein, and the stationary cutter B, coming with its end against the inner side of wall A and opposite to the opening a , is prolonged therethrough by bolt b , screwing into the end of the stationary cutter, and having a diameter corresponding to that of the opening a .

The stationary cutter B has an angular 70 shoulder on the end or ends thereof, which takes into a similar depression or recess in the side wall, A, which prevents its rotation, and yet admits of a limited vertical movement of the cutter, as is clearly shown.

c is a screw-pin projecting outward from the wall perforated by opening a , and near the edge of said opening, and D is a disk perforated axially to receive the bolt b as a journal, and provided upon its inner face with a 8c spiral groove engaging with the screw-pin c .

The bolt b is provided with a head, as shown, to bear upon the back of the disk, and the disk is adapted to be rotated by any convenient form of spanner or wrench.

When assembled, as seen in Fig. VII, and it is desired to adjust the stationary cutter B to the rotary cutter, the bolt b is turned a short distance to release disk D, which is then rotated to move, by means of its spiral groove 90 and the screw-pin c , the stationary cutter to the required point, to which it is held by simply again tightening the bolt b .

In Fig. VIII an adjustable journal-bearing for the rotary cutter-shaft C is shown. This 95 bearing is formed of a sleeve, E, on said shaft, which is received in a socket or recess in wall A, within which socket the sleeve rests. The shaft C has its bearings in wall A. A cam-surface, e , is formed on the bottom of the 100 socket or recess, which corresponds with a similar cam-surface, e , upon one end of sleeve

E. *f* is a binding-screw for securing sleeve E in place. *f'* is an angular head, by means of which the sleeve is adjusted.

The sleeve E is shown in dotted lines provided with a conical mouth bearing against a corresponding shoulder upon shaft C, though vertical shoulders upon both surfaces would answer the same purpose.

As the journal-surfaces of sleeve E and shaft C become worn, the set-screw *f* is loosened, and the sleeve E rotated by its head to take up the wear, and being in the required position, is secured there by the screw *f*.

The handle-holder, in combination with one fork of a handle, is as follows: A bolt, G, uniting the disks H on and integral with opposite side walls, A, of the machine, has an outwardly-projecting head, *g*, forming a flange upon said bolt, the inner face of which is the thickness of one fork, K, removed from the face of the disk.

The projecting part of bolt G forms a fulcrum at times for the fork K to be rotated upon. Upon one side of the bolt, and raised from the face of the disk, is a block, *h*, one side of which forms a bearing for the end of fork K when in the position shown in full lines in Fig. X—its operative position—while the other side of said block forms a bearing for the fork when in the position shown in dotted lines in the same figure, and when the handle is swung over the machine. Upon the opposite side of bolt G from block *h* is a block, *i*, forming, with block *h*, a support for the fork K in either position shown in Fig. X.

Connecting the two blocks *h* *i* is a segmental rim, *m*, having the axis of the bolt G for its center and removed from the longer bearing side of block *i*, to leave a shoulder or second bearing side thereto.

The fork K has upon its end a hook, *n*, which catches against this shoulder of block *i* when the fork is in the position indicated by dotted lines, Fig. X, while the rim *m*, by contact with the end of hook *n*, holds the fork beneath the bolt G in revolving and at other times, and so causes the bolt-head to be sufficient to retain the fork K to the disk H.

The end of fork K is of the configuration shown, with curved inner and outer edges having the axis of bolt G as their center when in the operative position shown in Fig. X. When the machine is being operated, the forks of the handle bind upon the bolt G as an axis and fulcrum. To place the fork in the position indicated in dotted lines in the same figure, it is simply oscillated, and may be restored to an operative position again by simply pulling over the handle, permitting the weight of the fork to bear against the bolt; but when the fork is in the position shown in dotted lines, Fig. X, and it is desired to remove the handle, the entire weight is allowed to rest upon the block *i* and rim adjacent thereto, and the fork K is rolled upon the block *i* as a fulcrum to entirely clear it from the bolt G with its head, and so leave it free to be entirely removed.

This is shown in Fig. XI, and in replacing the handle it is only necessary to let the hook *n* follow down the longer side of block *i* until it passes over the shoulder thereof, when the handle can be swung into either position shown in Fig. X.

In this device the head of the bolt, required at this point to assist in framing the sides of the machine, is the only thing needed to retain the fork of the handle to the other parts of the disk, and the handle, with its forks, may be removed or replaced instantly without care.

My traction-roller consists of a series of 80 wheels, I, having a number of corrugations, *o*, in their peripheral rims *p*, and having hubs provided with clutches formed of teeth *r* and interdental spaces *s* proportioned in number to the corrugations upon the wheel-rims, so 85 that one wheel may be clutched with the next wheel, to either hold the two, as shown in the first two wheels, Fig. XIII, with the ends of the corrugations opposite and in contact, or, as seen in the second and third wheels, with 90 the sides of the corrugations in close contact.

The wheels I are journaled upon the usual axle, J, and through the last wheel, (not shown,) are clutched to the driving-gear of the machine.

The clutches upon the hubs are made long enough to engage in either relative position of adjacent wheels, and the machines are supplied with a number of wheels I sufficient to build the roller up as a solid drum, by the removal of more or less of which and the adjustment of the remainder the weight and traction or holding-surface of the roller may be varied at will.

In the case of newly-seeded ground, where 105 the resistance to the knives is slight and less traction is needed, and where a weighted roller would be of advantage to the grass itself, the roller may be used solid; but where the sod is heavy a roller built up of alternate wheels I, 110 arranged as the first two wheels in Fig. XIII, works to advantage by the great hold the roller takes upon the sod, which penetrates the interstices between the individual wheels.

The journal and bearing of my truck-wheel 115 are constructed as follows: Upon the truck-arm L is a stud, *d*, having an angular bolt-opening, *a'*, therethrough. Upon the stud *d*, with its base against the truck-arm, is placed a washer, O, of the configuration of a truncated cone. Spurs *o'* from the base of washer O, received in opposite depressions, *l*, in the face of truck-arm L, prevent any rotation of washer O on the stud as its axis. The truck-wheel W, axially counterbored to half of the 125 depth of its hub to correspond to the cone-surface of washer O, is placed over and rests upon said washer. The wheel W is similarly counterbored in its hub to the center from each end thereof, and when resting upon 130 washer O a washer, R, is placed over the stud to fill the remaining conical bore of the wheel and have its inner end come nearly in contact with that of washer O. A bolt, *t*, having a

square shoulder to fit the opening a' , and a retaining-head coming against the outer side of truck-arm L, is passed through the stud d, and a nut, t' , and washer t' , upon its projecting 5 threaded end, are brought against washer R, to clamp the wheel and its two-part bearing to the truck-arm. As shown in Fig. XVI, the inner ends of the washers O R are not in contact, being held apart by the cone-faces of the 10 wheel-bearing, the space thus left permitting the approach of the washers in the wheel and on the stud, in taking up, by means of the screw-nut upon bolt t , the wear of the journal-surfaces, and the conical washers, while not in contact, 15 are held from rotating by spurs w from one entering recesses y upon the near face of the other. The stud d does not extend through the combined washers, so that a space between its end and the inner face of the washer t' permits 20 the washer R, nut, and washer t' to move longitudinally upon the bolt t . By these means a tight joint is formed at the journal to exclude all dust and moisture, and all wear of the journal-surfaces may be compensated for 25 by the tightening of the joint.

Now having described my invention, what I claim is—

1. In lawn-mowers, a stationary cutter, B, having an end guided to move in one direction 30 in the side wall, A, wall A having opening a therethrough elongated in the direction of movement of cutter B, screw-pin c , projecting from wall A near the outer edge of opening a , spirally-grooved disk D, engaging with screw-pin c , and adapted to be rotated by a wrench, and bolt b , arranged to pass as an axis through spirally-grooved disk D, and through opening a , to screw into cutter B, and provided with a 35 head adapted to come against and hold the spiral-groove disk to the screw-pin and bind it in the position in which it may be set, as and for the purpose set forth.

2. A lawn-mower cutter-shaft, C, having an 40 end shoulder thereto, a sleeve, E, upon said shaft socketed within the side wall, A, and having a shoulder corresponding to that of the shaft and bearing against it, said sleeve provided with an angular head, adapting it to be 45 rotated by a wrench, two pairs of corresponding cam-surfaces, $e e'$, upon the sleeve E and fixed wall A, respectively, adapted to cause the sleeve E an endwise movement upon being rotated, and a binding-screw, f, from the wall A, bearing upon sleeve E, to hold the same 50 thereto, all combined and operating as and for the purpose set forth.

3. In lawn-mowers, a disk, H, prolonged 55 from a side wall, A, a stud-bolt, G, projecting outward therefrom centrally, and having a head, g , a block, h , raised from the disk-face

upon one side of stud-bolt G, a block, i , upon said disk-face upon the opposite side of stud-bolt G from the one h , having a space between it and the stud-bolt, a segmental rim, m , connecting blocks i and h , having the axis of stud-bolt G for its center, and leaving a radial shoulder to block i , and a fork, K, adapted to rest flat upon the disk-face, of width enabling it to pass under stud-bolt head g , provided with a hook end, n , adapted to bear upon the shoulder of block i and rest upon rim m , having an inner curved edge conforming to stud-bolt G, and an outer curved edge starting from hook n , and a shank whose parallel edges are tangential to its curved edges, and an end edge 75 extending from the hook end n radially to the bolt, and presenting a surface coinciding with one side of the block h when the shank is resting upon block i , and having its shank coinciding with block h when its hook end is 80 resting against the shoulder of block i , and adapted from said configuration to be rocked upon block i , to have its end released from block i , and from bolt G and its head g , substantially as shown and described.

4. A traction-wheel for lawn-mowers, consisting of the combination, with an axle, J, of a series of wheels, I, uniformly corrugated upon each lateral edge of their peripheral rims, and each provided with a journal-bearing in 90 the form of a hub, having clutch-teeth upon each end, and adapting said wheel to be clutched with an adjacent one on axle J, to cause the corrugations of both to interlock, or have their projecting curves or salient angles 95 in contact, as and for the purpose set forth.

5. The within-described truck-wheel and wheel-bearing for lawn-mowers, consisting of a stud, d, upon truck-arm L, a wheel-hub having a journal-bearing conically counter-bored from its ends to the center of the hub, two cone-washers having their faces coinciding with the journal-bearing surfaces of the hub, and arranged upon the stud, their ends truncated and held to each other and to the arm L 100 from rotation, spurs upon the washers, and a screw-bolt, t, passing from arm L through the stud, and held therein from rotation, and provided with a nut and washer upon its projecting end removed from contact with the 105 end of the stud and bearing upon one conical washer, all arranged substantially as shown, and operating to take up all wear of the journal-surfaces upon the tightening of the nut upon its bolt.

WILLIAM L. FRISBIE.
